MAGNETIC SEPARATOR

L. V. Andrews and Harold F. Walton, Worcester,
Mass., assignors to Riley Stoker Corporation,
Worcester, Mass., a corporation of Massachusetts

Application June 28, 1934, Serial No. 732,910

7 Claims. (Cl. 209—219)

This invention relates to magnetic separators, and more particularly to separators of the electro-magnetic type having an iron core surrounded by a coil of insulated wire, these parts being arranged to set up a strong magnetic field and produce a separation of particles of iron from non-magnetic material. In the specification and claims the word "iron" is used in a broad sense to include all magnetic materials, whether the word is applied to the particles to be separated or to portions of the separator itself.

Magnetic separators of this type are ordinarily energized by a direct current, and when the circuit is opened, either intentionally by means of a switch or accidentally by reason of a broken wire, the powerful magnetic field will suddenly collapse. This will momentarily induce a very high voltage in the coil, which may result in a breaking down of the insulation. In order to avoid this danger, it has been the practice to utilize special switches which connect a resistance across the coil just prior to the opening of the connection with the line. These switches are expensive, they cause a surge in the line when they are operated, and they provide no protection in case of an accidentally opened circuit.

It is accordingly one object of the invention to provide a magnetic separator which is so constructed and arranged that no unduly high voltage will be induced in the coil when the circuit therethrough is opened.

It has previously been proposed to construct magnetic separators in the form of a rotating drum which surrounds a stationary electro-magnetic net. A stream of mixed iron and non-magnetic material is delivered to the outer surface of the drum, and the iron particles adhere to the drum and are carried out of the stream. In these prior constructions it has been found difficult to obtain a sufficiently strong magnetic field to hold large iron particles without using large and expensive coils, and if the field is made sufficiently strong the smaller iron particles will not be released from the drum. In some cases coils of special and expensive distorted shapes have been utilized in an attempt to provide satisfactory operation.

It is accordingly a further object of the invention to provide a magnetic separator of the type having a stationary electro-magnet surrounded by a rotatable drum, which will produce a very strong magnetic field at one side of the drum and practically no field at another side.

It is a further object of the invention to provide such a separator which will be comparatively

small, compact and inexpensive, and which preferably comprises coils of a simple cylindrical shape.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts.

Fig. 1 is a sectional elevation of a magnetic separator, the section being taken on the line 1—1 of Fig. 3;

Fig. 2 is a perspective view of the coil supporting structure, with the coils and sleeves removed;

Fig. 3 is a section on the line 3—3 of Fig. 1;

Fig. 4 is an elevation of the drum which surrounds the coils;

Fig. 5 is a section on the line 5—5 of Fig. 1; and

Fig. 6 is a perspective view of the iron pole pieces for the drum before the drum is cast thereon.

The embodiment illustrated comprises a casing having two spaced vertical side walls 10 connected by an end wall 11 to provide a structure substantially U-shaped in cross-section, as shown particularly in Fig. 5. Each side wall 10 is formed with a circular opening 12 therein, these openings being coaxial. Cover plates 14 and 15 are mounted over the openings, and a cylindrical iron bar 16 extends horizontally across the casing and is supported at its ends in the cover plates. The parts so far described are preferably made of iron.

A cylindrical drum 17 surrounds the bar 16 concentrically, and is arranged to be rotated by a suitable means. As illustrated the drum is supported on end plates 18 and 19 rotatably mounted on ball bearings 20 on the bar 16. The plate 18 is provided with an annular flange 21 having a groove 22 therein to receive a driving belt 23. The drum 17 is arranged to provide moving pole pieces, and for this purpose the drum is formed of a main body of non-magnetic material, such as brass, having inserts 25 of iron in the form of rectangular bars extending parallel to the axis of the drum. These bars are arranged with their inner and outer surfaces flush with the corresponding surfaces of the non-magnetic portion of the drum. The bars 25 are preferably made alternately long and short, as shown particularly in Fig. 4, since this provides a more

uniform distribution of the magnetic flux longitudinally of the drum.

While the drum 17 may be manufactured in various ways, we prefer to first form by casting or otherwise a unitary iron structure as shown in Fig. 6, in which the bars 25 are held in their proper relative positions by means of a surrounding circular band 26. This structure is placed in a suitable mold and the brass is cast about the bars. The casting is then taken from the mold, and the band 26 removed by a suitable machining operation in a lathe or otherwise. The sides of the bars 25 which contact with the brass are made convex so that the bars are firmly held in place in the brass casting. The drum is preferably machined both inside and outside in order to provide smooth and accurate cylindrical surfaces, and it is shown slightly smaller in diameter than the openings 12 so that it may be readily removed or inserted therethrough.

In order to provide the necessary magnetic flux, we mount a stationary electro-magnet within the drum 17. This magnet comprises a central iron pole piece 28 supported on the iron bar 16 or core 16 half-way between the end plates 18 and 19 and in line with the centers of the bars 25. The pole piece 28 is shaped as a circular sector located in a plane perpendicular to the axis of the drum and extending through a large angle, in fact nearly 180 degrees. The pole piece 28 projects from the core 16 in a direction toward the casing wall 11, and the periphery of the pole piece is very close to the inner surface of the drum. At each side of the central pole piece is an electrical coil 30 cylindrical in shape and having an outside diameter somewhat smaller than the inside diameter of the drum 17. The coils 30 are preferably identical and they surround the core 16, which is bored axially at 31 for suitable leads (not shown) through which electric current is conducted to the coils. Between each end plate and the adjacent coil we preferably provide a plate 32, preferably of iron, which is similar in shape to the pole piece 28 but somewhat thinner and formed with a narrow radial arm 33 extending in the opposite direction from the main body of the plate. These arms 33 serve to support an arcuate iron plate 35 which extends substantially the entire length of the drum 17 and close to the inner surface thereof.

In order to prevent possible damage to the insulation of the coils 30 as a result of high voltage generated therein upon opening of the circuit and sudden collapse of the magnetic field, we provide means forming a low resistance path for the flow of induced current around the core 16. For this purpose we prefer to mount a sleeve 37 of copper or other highly conductive non-magnetic material inside of each coil and surrounding the core. When the magnetic field collapses, a comparatively large induced current flows momentarily in the low resistance path afforded by the sleeve and as a result there is no dangerously high voltage produced in the coil.

The material which is to be separated is delivered to the outer surface of the drum 17 by any suitable means. In the drawings we have shown for this purpose a chute or trough 40 mounted above the drum and sloping downwardly toward the casing wall 11. On each side wall 10 adjacent to the chute 40 there is mounted a flanged guard member 41, preferably of non-magnetic material, which overlies the adjacent end portion of the drum 17 to prevent the stream of material from contacting there-

with. Beneath the drum 17 there is provided a partition 43 (Fig. 1) forming a division between the space 44 adjacent the casing wall 11 and the space 45 in which the iron particles are to be deposited.

The operation of the invention will now be apparent from the above disclosure. A direct current is supplied to the coils 30, the connections being such that the magnetic flux produced by one coil opposes that produced by the other. This flux passes outwardly from the core 16 through the pole piece 28, which becomes strongly magnetized, and into such of the bars 25 as happen to be adjacent to the pole piece. If the direction of the current is such that the member 28 is a north pole, the bars 25 will also be north poles and in effect lateral extensions of the pole piece. From these bars a large part of the flux will travel in laterally diverging directions across to the casing end wall 11 and side walls 10, the casing forming a magnetic south pole from which the flux returns to the ends of the core 16. The reluctance of this return path may be decreased by forming the cover plates 14 and 15 of iron. Some of the flux will return to the core through the end plates 18 and 19, particularly if they are made of iron, and also through the plates 32. Non-magnetic material which is delivered by the chute 40 will pass over the drum 17 and drop into the space 44, while iron pieces which may have been mixed with said material will be strongly attracted by the magnetized iron bars 25. As a result, rotation of the drum in an anti-clockwise direction as viewed in Fig. 1 will cause the iron pieces to be carried over the top of the partition 43 to a position above the space 45. When the bars 25 leave the pole piece 28 they will lose most of their magnetism and the iron pieces will fall therefrom. A slight residual magnetism may remain in the bars 25, however, and cause them to hold some of the smaller particles of iron until the bars reach a position close to the plate 35. Since this plate is connected to the ends of the core 16 by means of the narrow iron arms 33, it will be given a comparatively weak magnetism which opposes and hence neutralizes the residual magnetism of the bars, allowing the small iron particles to fall.

When an iron body is in contact with one of the bars 25 adjacent to the pole piece 28, the path from the core 16 to the iron body is completely iron except for the air gap between the pole piece and the bar, and this air gap can be made very small. As a result the iron body will be held firmly against the bar. The coils 30 are of a simple cylindrical shape and hence are comparatively inexpensive. They may be connected in parallel for one voltage, say 110, and in series for a higher voltage such as 220.

If the circuit through one of the coils is opened, either accidentally or intentionally, the sudden collapse of the magnetic field will simply produce a momentary induced current in the low resistance path afforded by the copper sleeve 37. As a result, the production of dangerously high induced voltages in the coil is avoided. No special and expensive switches are required, and no line disturbances are created.

Having thus described our invention, what we claim as new and desire to secure by Letters Patent is:

1. A magnetic separator comprising an iron core, an electrical coil surrounding the core and arranged to set up a magnetic field, means to direct a stream of mixed magnetic and non-magnetic

material into the field and thus effect a separation of the magnetic and non-magnetic material, and means forming a low resistance path through which induced current may flow around the core upon collapse of the field, whereby the coil is protected from high induced voltages.

2. A magnetic separator comprising an iron core, a sleeve surrounding the core and formed of non-magnetic material having a high electrical conductivity, an electrical coil surrounding the sleeve and arranged to set up a magnetic field, and means to direct a stream of mixed magnetic and non-magnetic material into the field and thus effect a separation of the magnetic and non-magnetic material, the sleeve forming a low resistance path through which induced current may flow around the core upon collapse of the field, whereby the coil is protected from high induced voltages.

20 3. A magnetic separator comprising an iron core, a copper sleeve surrounding the core, an electrical coil of insulated wire surrounding the sleeve and arranged to set up a magnetic field, and means to direct a stream of mixed magnetic and non-magnetic material into the field and thus effect a separation of the magnetic and non-magnetic material, the sleeve forming a low resistance path through which induced current may flow around the core upon collapse of the field, whereby the coil is protected from high induced voltages.

4. A magnetic separator comprising a substantially horizontal iron core, two electrical coils surrounding the core and spaced apart axially, an iron pole piece extending radially from the core and located between the coils, the pole piece being shaped as a circular sector, a rotatable cylindrical drum surrounding the coils, the drum having a main body of non-magnetic material and a series of iron bars supported therein and parallel to the axis of the drum, the bars being alternately long and short, and means to deliver a stream of mixed magnetic and non-magnetic material to the outer surface of the drum.

45 5. A magnetic separator comprising a substantially horizontal iron core, two electrical coils surrounding the core and spaced apart axially, an iron pole piece extending radially from the core and located between the coils, iron arms extending from the end portions of the core in the opposite direction from the pole piece, an iron mem-

ber extending parallel to the core and connecting the outer ends of the arms, a rotatable cylindrical drum surrounding the coils and arranged to provide iron pole pieces which revolve close to the first mentioned pole piece and the iron member, and means to deliver a stream of mixed magnetic and non-magnetic material to the outer surface of the drum at a region near the first mentioned pole piece.

5 6. A magnetic separator comprising a substantially horizontal iron core, two electrical coils surrounding the core and spaced apart axially, an iron pole piece extending radially from the core and located between the coils, the pole piece being shaped as a circular sector, iron arms extending from the end portions of the core in the opposite direction from the pole piece, an arcuate iron member extending parallel to the core and connecting the outer ends of the arms, a rotatable cylindrical drum surrounding the coils, the drum having a main body of non-magnetic material and a series of iron bars supported therein and parallel to the axis of the drum, the bars being arranged to revolve close to the pole piece and said iron member, and means to deliver a stream of mixed magnetic and non-magnetic material to the outer surface of the drum at a region near the pole piece.

10 7. A magnetic separator comprising a substantially horizontal iron core, two electrical coils surrounding the core and spaced apart axially, an iron pole piece extending radially from the core and located between the coils, the pole piece being shaped as a circular sector, iron plates extending from the end portions of the core in the same direction as the pole piece, each plate being shaped as a circular sector, an iron arm extending in the opposite direction from each plate, an arcuate iron member extending parallel to the core and connecting the outer ends of the arms, a rotatable cylindrical drum surrounding the coils, the drum having a main body of non-magnetic material and a series of iron bars supported therein and parallel to the axis of the drum, the bars being arranged to revolve close to the pole piece and the iron member, and means to deliver a stream of mixed magnetic and non-magnetic material to the outer surface of the drum at a region near the pole piece.
